UNITED STATES PATENT OFFICE.

LOUIS FRITZ, OF LOS ANGELES, CALIFORNIA.

RAIL-FASTENING DEVICE.

1,354,292.

Specification of Letters Patent. Patented Sept. 28, 1920.

Application filed October 21, 1919. Serial No. 332,327.

To all whom it may concern:

Be it known that I, LOUIS FRITZ, a citizen of the Dominion of Canada, British North America, residing at Los Angeles, in 5 the county of Los Angeles and State of California, have invented new and useful Improvements in Rail-Fastening Devices, of which the following is a specification.

The invention has particular reference to 10 rail fastening devices by which the parallel rails of a railroad track are securely fastened to the cross ties of the track and braced and connected together in such a manner that they will not spread.

15 The invention is in the nature of a pair of rail chairs provided with means for effectively clamping the rails to the cross ties and provided with means whereby the rail chairs are connected together so as to prevent them from relative movement.

With the above and other objects in view, the invention consists of the novel features of construction, and the combination and arrangement of parts as are hereinafter 25 fully described and claimed.

In the accompanying drawing in which similar reference characters are used to designate corresponding parts throughout the several views:

30 Figure 1 is a cross sectional view of a railroad track, a tie and one of the devices constructed in accordance with this invention being shown in side elevation.

Fig. 2 is a top plan view of a portion of 35 the railroad track and one of the devices.

Fig. 3 is a detail longitudinal sectional view taken substantially on the plane indicated by the line 3—3 of Fig. 2.

Fig. 4 is a top plan view of one of the 40 base plates.

Fig. 5 is a perspective view of one of the outer rail braces.

Fig. 6 is a similar view of one end of one of the tie plates.

45 In the embodiment illustrated the numeral 1 designates one of the cross ties of a railroad track. Placed on the upper side of the tie adjacent its ends is a pair of base plates 2, which are preferably of rectangular configuration having their outer ends upturned along their entire length as indicated at 3 to form flanges and the side portions of their inner ends upturned as indicated at 4 to form pairs of short flanges.

The intermediate portions of the inner ends 55 of the plates 2 are extended beyond the flanges in the plane of the plates, the extensions 5 thus formed being provided with elongated apertures 6. Plates 2 adjacent their outer ends are provided with a pair 60 of spike receiving apertures 7 and a pair of rivet receiving apertures 8, while the inner ends of the plates are provided with any suitable number, preferably three spike receiving apertures 9.

65 The numerals 10 designate outer rail braces which are formed from sheet metal plates of substantially rectangular configuration. These plates are adapted to be placed upon the outer ends of the base plates 70 2 and are provided with spike receiving apertures 11 arranged to aline with the apertures 7 and rivet receiving apertures 12 arranged to aline with apertures 8 of the plates 2. The outer edges of the brace 75 plates 10 abut or rest against the upturned ends 3 of the base plates. The intermediate portions of the brace plates 10 are pressed upwardly so as to form lugs or shoulders 13 adapted to bear against the webs of the adjacent rails. The inner edges of the plates 10 on opposite sides of the shoulders 13 are bent upwardly out of the plane of said plates 10 to extend over the base flanges of the rails. The plates 10 after being properly 85 positioned upon the base plates 2 are riveted to the latter by means of rivets 14 which are extended through alined openings 8 and 12.

80 The invention also contemplates the use 90 of inner rail braces 15, which are also substantially rectangular in configuration and are provided at their outer edges with upwardly and outwardly inclined portions 16 adapted to fit over the base flanges of the 95 rails. These brace plates 15 are adapted to have their inner edges rest against or abut the upturned inner edges or flanges 4 of the base plates 2. The plates 15 are provided with apertures arranged so as to aline with 100 the apertures 9 in the base plates 2.

105 The numeral 17 designates a tie plate which is long and narrow and has its ends downturned for engagement with openings 6 in the base plate 2. The intermediate portion of the tie plate 17 is provided with a spike receiving aperture.

In assembling the complete device, the

outer braces 10 are placed upon the outer ends of the base plates 2 and riveted thereto by means of the rivets 14. The base plates carrying the outer braces are then placed in proper position upon the tie 1 and spikes 18 are passed through the alined openings 7 and 11 and into the tie. The rail sections 19 are then placed upon the base plates 2 with the outer portions of their base flanges inserted under the upturned inner edges of the braces 10 and so that their webs abut against the shoulders 13 of the braces 10. The inner braces 15 are then put in position with their inner ends resting against the upturned inner end portions of the plates 2 and with their upturned outer ends engaging over the inner portions of the base flanges of the rail sections. Aper-tures in the braces 10 will then be alined 10 with the apertures 9 in the base plates 2, and spikes are then passed through these apertures and embedded in the tie 1. After the rail sections have thus been securely clamped to the base plates by means of the inner and outer braces, the tie plate 17 is placed upon the tie between the base plates with its downturned ends inserted through the elongated apertures 6 of the base plates 2, and a spike 20 is driven through the intermediate aperture of the tie plate into the cross tie 1. This tie plate serves to hold the base plates 2 together so that they cannot move relatively to one another. Spreading of the rail sections is thereby prevented, and 15 in view of the fact that the rail sections are securely clamped to the base plates by means of the inner and outer braces, they will not work loose and cause derailment or accidents.

40 The invention is of simple, cheap and durable construction, is easily assembled or applied, and is well adapted for the purpose for which it is designed. Various changes in form, proportion and in the minor details 45 of construction may be resorted to without

departing from the spirit of the invention as defined in the appended claims.

I claim as my invention:

1. A device of the class described comprising a pair of substantially rectangular base plates having their outer ends upturned and their inner ends provided with lateral extensions and upturned portions, outer rail braces riveted to the outer ends of said base plates and having their outer edges abutting the upturned outer ends of said base plates, inner rail braces secured to the inner ends of said base plates and having their inner edges abutting the upturned inner ends of said base plates and the adjacent ends of said braces being shaped to receive and clamp rail sections thereunder, and a tie plate having its ends coupled to the extensions of said base plates. 50 55 60

2. A device of the class described comprising a pair of base plates, outer rail braces secured to the outer ends of said base plates, the intermediate portions of said braces being pressed upwardly to form web engaging shoulders, the inner edges of said outer braces on opposite sides of said shoulders being provided with upwardly extending flanges adapted to engage the base flanges of the rail sections, inner rail braces secured to the inner ends of said base plates and provided at their inner edges with upwardly extending flanges adapted to engage the base flanges of the rail sections, and a tie plate having its ends coupled to said base plates to prevent the 70 75 80 latter from moving relatively to one another.

In testimony whereof I have hereunto set my hand and signed these specifications at and in the city of Los Angeles, county of Los Angeles, State of California, on this the 15th day of October, A. D. 1919.

LOUIS FRITZ.
